UNITED STATES PATENT OFFICE

EDMUND D. MEAGHER, OF SOUTH BEND, INDIANA, ASSIGNOR TO THE
ECONOMIST PLOW COMPANY, OF SAME PLACE.

PLOW.

SPECIFICATION forming part of Letters Patent No. 275,683, dated April 10, 1883.

Application filed November 21, 1882. (No model.)

To all whom it may concern:

Be it known that I, EDMUND D. MEAGHER, of South Bend, in the county of St. Joseph and State of Indiana, have invented a new and useful Improvement in Plows; and I do hereby declare that the following is a full, clear, and exact description of the same.

My invention relates to plows, and is an improvement more especially upon the form of plow shown in Letters Patent granted me on the 17th day of February, 1882, No. 253,408.

The object of my invention is to simplify the construction and to further strengthen the parts where weakest in the respects hereinafter explained, to the end that my improved plow with independently-reversible point and wing may be constructed as cheaply as an ordinary plow without impairing its necessary strength or departing from the simplicity required in use.

The first part of my invention consists of an improvement in the foot of the standard and in the reversible point fitted thereto. The second part relates to means for strengthening the foot of the standard at a point where the hooked bolt passes through it to draw back and hold the point.

In the drawings, Figure 1 represents a bottom view of a plow embodying my improvements. Fig. 2 is a side view of the land side of the plow. Figs. 3 and 4 are detached views of a portion of the foot of the standard. Fig. 5 is a detail of the point and wing; Fig. 6, a detail.

In my said patent the bearing-piece for the point, which passed through the opening in said point, was not made to extend quite to the surface thereof, so as to be flush with the surface of the point and landside. The side of the point, as shown in Fig. 4 of the said patent, was adapted to receive a plate, as shown in Figs. 1 and 5, which plate covered the otherwise exposed face of that part of the standard upon which the point rested.

In my present invention I simplify the construction by extending the part which supports the point to bring it flush with the surface of the side of the said point, whereby it is made to fill the whole recess and present a smooth surface on the land side. I thus dis-

pense with the covering-plate and simplify the form of the point, thus rendering it easier to fit the parts and reducing the expense. The lateral projection which forms the bearing for the point is shown at *a* in Figs. 2 and 3. It is cast so as to exactly fit the recess in the point *A*. This point is in all respects like that shown in my said patent, excepting that it is not rabbeted to receive the plate, and that the web 1 in the present improvement is of the same width as the upper and lower flanges, 2 2. The edge of the web 1, when the point is in place, is therefore flush with the landside and with the outer surface of the part *a*. The hook-bolt 7, which holds the point in place, passes through the hole 16 in the vertical flange on the side of the standard-foot, and projects in front of the web 1, one corner of the part *a* being slightly rounded out to receive the hooked end, as shown in Fig. 2. The foot of the standard is somewhat weakened by the hole 16, and this and the form required in order to give place to the hooked bolt have rendered it necessary heretofore to make the standard of malleable iron, which has increased the expense of this construction. In order to obviate the difficulty, I have devised the form shown in Figs. 3 and 4, in which a bridge, 17, is thrown across from the vertical flange 18 of the standard-point to the bottom plate, 19. This leaves a cavity, 20, for the hook, the bridge extending forward and covering the whole cavity to the point and edge of the bottom plate. This gives all the necessary strength for the foot of the standard and makes it practicable to cast the standard of common gray iron. It does not practically increase the weight of the plow when in use, as the cavity in the previous construction is usually filled with dirt.

In my former patent heretofore referred to the wing *C* was joined to the point by means of a tapering bevel fitting into the recessed sides of the point. I find that this construction can be advantageously simplified by shaping the edge of the point with a plain surface properly inclined to abut squarely against the plain edge of the point, the upper and lower surface of the point being rounded off, as shown at 21, Fig. 5. In all other respects the plow

shown is of the same construction as that described in my aforesaid patent.

Having thus described my invention, what I claim is—

1. A lateral projection, *a*, upon the end of the standard, in combination with the reversible point *A*, the said projection fitted to the recess in said point, and being flush with the side thereof when the point is in place upon the foot of the standard, substantially as described.
2. The standard-foot, as described, having

the projection adapted to receive the reversible plow-point, a hole adapted to receive the hooked rod to hold the plow-point in place, and the strengthening-bridge 17, substantially as described.

In testimony whereof I have signed my name to this specification in the presence of two subscribing witnesses.

EDMUND D. MEAGHER.
